UNITED STATES PATENT OFFICE.

CHARLES SCHULTZ, OF NEW YORK, N. Y.

HOLDER FOR DISK RECORDS.

1,374,240.

Specification of Letters Patent. Patented Apr. 12, 1921.

Application filed October 6, 1920. Serial No. 415,001.

To all whom it may concern:

Be it known that I, CHARLES SCHULTZ, a citizen of the United States, residing in New York, in the county of New York and State of New York, have invented certain new and useful Improvements in Holders for Disk Records, of which the following is a specification.

My present invention relates to improvements in holders for disk records.

One object of the invention is to provide a holder for record disks comprising a pad of leaves having thereon printed or illustrated matter associated with the rendering of the disk record contained within the holder; which leaves having the printed or illustrated matter may be stripped from the pad and distributed when the disk record is rendered among the hearers of the record for fixing the identity of the record upon the minds of the hearers; or for providing instruction or additional interest and enjoyment for the hearers of the record.

A further object is to provide a holder for preserving the record from dust, moisture or injury.

In the accompanying drawings which form part of this specification,

Figure 1 is a face view of my holder for record disks;

Fig. 2 is a sectional view on the line 2—2 of Fig. 1, looking in the direction of the horizontal arrow;

Fig. 3 is a fragmental perspective view; and

Fig. 4 is a view on the line 4—4 of Fig. 1, of a modified means for retaining the lower loose ends of the leaves of the pad of the holder, the holder or envelop, record disk and pad being in section.

My holder for record disks comprises in its main elements or parts a holder or envelop A, and a pad B.

The holder or envelop A is of paper or other suitable material, and preferably is substantially square in shape, each side being in length slightly more than the diameter of the record disk to be inclosed therein.

The holder or envelop A is composed of two sheets or body pieces, stitched, pasted or otherwise suitably secured together along the bottom 10 and sides 11 and 12, and open at the top 13. The top 13 is provided with a cut-out portion of each sheet, the cut-out portions forming a means, such as the arcuate recess 14, whereby the record

disk may be grasped for removing it from the holder or envelop A, and the holder or envelop may be provided, usually on its face side, with an opening, such as 14, for exposing illustrated or printed matter of the record disk.

The pad B consists of a plurality of leaves 15, pasted or otherwise suitably secured together at their upper ends, and loose or separate from each other at their lower ends, so as to permit the leaves to be removed severally or stripped from the pad B. Each leaf 15 has thereon illustrated or printed matter associated with the rendering of the particular disk record inclosed in the holder or envelop, such as the title of the record; information relative to the musical composition of which the disk is a record; or if the record be declamatory, relative to that; portions of the libretto of an opera from which the record is a musical excerpt; or the words of a song, as indicated in Fig. 1; the leaves to be distributed among the hearers of the record when the disk record is rendered.

The outer or face sheet of the holder or envelop A is provided with a band 16, preferably formed of the sheet by slitting or cutting the sheet, the back of the pad B being pasted or otherwise suitably secured to the outer or face sheet of the holder or envelop A and the band 16 being so located as to pass over and hold down or in place the loose ends of the leaves 15 of the pad B, that is, to prevent them from curling up or outwardly, as indicated by one of the leaves in Fig. 2, when the pad B is in the desired position on the holder or envelop A, but to permit the loose end of a leaf 15 to be withdrawn from under the band 16, and stripped from the pad B for distribution.

In Fig. 4, the band 17, the purpose of which is the same as the band 16, is a strip of paper or other suitable material, pasted or otherwise suitably secured to the outer or face sheet of the holder or envelop A, if in practice, such construction should be desirable as affording a band of greater strength than the band 16.

Having thus described my invention, I claim:

1. In combination, with a record disk, an envelop for inclosing the record disk; and matter associated with the rendering of the disk record, and in separable parts, secured to said envelop and arranged for stripping

therefrom for distribution when the disk record is rendered.

- 5 2. In combination, with a record disk, an envelop for inclosing the record disk; and a pad of leaves of matter associated with the rendering of the disk record, secured to said envelop and arranged for stripping the leaves from the pad for distribution when the disk record is rendered.
- 10 3. In combination, with a record disk, body sheets secured together at the sides and bottom and open at the top and forming an envelop for the record disk; a pad secured to one of the body sheets, the pad

comprising leaves of matter associated with 15 the rendering of the disk record, the leaves at one end of the pad being secured together and being loose at the other end thereof for stripping the leaves from the pad; and means appurtenant to one of the body 20 sheets for preventing curling of the loose ends of the leaves and permitting stripping of the leaves from the pad for distribution when the disk record is rendered.

CHARLES SCHULTZ.
